UNITED STATES PATENT OFFICE.

FELIX PIOTROWSKI, OF NEW YORK, N. Y.

DESIGN FOR A POCKET-TOOL.

48,871.

Specification for Design.

Patented Apr. 11, 1916.

Application filed February 16, 1915. Serial No. 8,634. Term of patent 7 years.

To all whom it may concern:

Be it known that I, FELIX PIOTROWSKI, a subject of the Czar of Russia, residing at New York, in the county of New York and State of New York, have invented a new, original, and ornamental Design for a Pocket-Tool, of which the following is a specification, reference being had to the accompanying drawing, forming part thereof.

The figure is a view in perspective of the article, showing my new design.

I claim:

The ornamental design for a pocket tool, as shown.

FELIX PIOTROWSKI.

Witnesses:

JOHN KOVARČIK,

PAUL YZOR KOWYZ.
